JOSEPH LE CONTE DAVIS, DECEASED, LATE OF PITTSBURGH, PENNSYLVANIA, BY
MYRA SHIELDS DAVIS, ADMINISTRATRIX, OF PITTSBURGH, PENNSYLVANIA,
ASSIGNOR TO WESTINGHOUSE ELECTRIC AND MANUFACTURING COMPANY, A
CORPORATION OF PENNSYLVANIA.

ELECTRIC LOCOMOTIVE.

1,241,498.

Specification of Letters Patent.

Patented Oct. 2, 1917.

Application filed June 29, 1914. Serial No. 847,814.

To all whom it may concern:

Be it known that JOSEPH LE CONTE DAVIS, deceased, late of Pittsburgh, in the county of Allegheny and State of Pennsylvania, 5 during his lifetime invented certain new and useful Improvements in Electric Locomotives, and that I, MYRA SHIELDS DAVIS, administratrix of the estate of the said JOSEPH LE CONTE DAVIS, deceased, do hereby 10 declare to the best of my knowledge and belief that the following specification, taken in connection with the drawings furnished and forming a part of the same, is a clear, true, and complete description of said improvement.

The invention relates to electrically propelled vehicles, and it has special reference to electric locomotives such as are employed for hauling heavy trains upon electric rail- 20 way systems and electrified railroad systems.

The object of the invention is to provide an electric locomotive having a running gear upon which the driving motors are 25 mounted in a simple and improved manner, which permits of ready overhauling of the motor armatures through openings in the side frames.

According to the invention, openings are 30 provided in the side frames of the locomotive running gear into which suitable detachable bearing housings are disposed for the purpose of supporting the motor armatures, said side frame openings being of sufficient dimensions to permit the endwise removal of the armatures.

In the accompanying drawing, Figure 1 is a view, partially in section and partially in side elevation, of a locomotive constructed in accordance with the invention; Fig. 2 is a view, partially in section and partially in plan, of the running gear shown in Fig. 1; and Fig. 3 is a view, in side elevation, of one of the driving units shown in Figs. 1 45 and 2, the side frame of the locomotive being removed for the sake of clearness.

Referring to the drawing, the structure shown comprises a locomotive body 1 and a running gear 2 comprising a plurality of side frames 3 and 4, driving axles 5 and 6, driving wheels 7 and 8, a plurality of electric driving units 9 and 10 and mechanical driving connections 11 and 12 for trans-

mitting the driving effort of the driving units 9 and 10 to the wheels 7 and 8. 55

The side frames 3 and 4 of the running gear are mechanically associated by a plurality of cross-ties 14 which may also serve to support the driving units 9 and 10. The side frames 3 and 4 are provided with a plurality of openings 15 which are correspondingly disposed and adapted to receive a plurality of detachable bearing housings 16. Moreover, the side frames 3 and 4 are provided with pedestal openings 17 and 18 into which countershafts 19 and 20 are disposed and supported in bearing blocks 21 of any well-known construction.

Each of the countershafts 19 and 20 is provided, at one end, with a gear wheel 22 70 which is adapted to transmit the effort of the driving units 9 and 10 to the driving wheels 7 and 8 through cranks 23 and 24 and side rods 25.

Each of the driving units 9 and 10 embodies a plurality of rotatable motor armatures 26 which are symmetrically disposed about the countershaft 19 or 20 and are associated with a magnetizable field structure 27 having a single magnetic circuit, as 80 shown in Fig. 3 and fully set forth in Patent No. 1,186,755, issued June 13, 1916, and assigned to the Westinghouse Electric and Manufacturing Company.

So far as the present invention is concerned, the specific structure of the driving units 9 and 10 is immaterial and it is therefore not attempted to further describe the peculiarities thereof. It should be noted, however, that the configuration of the field 90 magnet structure 27 is such that it is impossible to remove the motor armatures 26 except in a lateral direction.

The several armatures 26 are carried upon shafts 28 in the usual manner, and one end 95 of each of the shafts is provided with a pinion 29 which is adapted to mesh with the gear 22, whereby all of the motor armatures 26 transmit their driving effort to the countershaft 19 or the countershaft 20. The 100 field magnet structure 27 may be supported intermediate the side frames 3 and 4 in any suitable manner, although it is proposed to utilize the cross-ties 14 for that purpose.

The several bearing housings 16, which 105 are adapted to be seated in the side frame

openings 15 and to be attached to the side frames 3 and 4 by bolts 30, or other adequate means, are adapted to receive the ends of the armature shafts 28 and to provide 5 bearings therefor. It is of particular importance that the openings 15 in the side frame 3, which are opposite to the pinions 29 and gears 22, be of dimensions somewhat in excess of the diameter of the motor armatures 26, although it is unnecessary that the correspondingly located openings 15 in the other side frame 4 be of the same relative proportions.

By this relationship and arrangement of 15 parts, it is rendered convenient to overhaul the motor armatures 26 through the side frame openings 15 on the side opposite the gearing, by removing the associated pinion 29 and detaching the bearing housing 16 20 which coöperates with the side frame 3. The removal of the motor armature 26 through the side frame 3 is necessitated by reason of the gear 22 on the opposite side which would interfere with the over-hauling in the other direction.

In its broadest aspect, the invention is not restricted to the particular type of driving unit shown and described, and, in fact, is not limited to a multi-armature structure, 30 but may be embodied in a driving unit having a single armature which is carried by bearing housings in the side frames, in the manner set forth.

It is to be understood, therefore, that the 35 appended claims are intended to cover all modifications of the invention which do not depart from the spirit and scope thereof.

It is claimed as the invention:

1. In a vehicle having driving wheels, the 40 combination with a plurality of side frames, a motor mounted between said frames, and a driving mechanism associated with said motor and disposed outside of said side frames, of means for supporting said motor in said 45 side frames, permitting the removal of one of its members through the side frame and maintaining the position of the driving wheels relative to said side frames.

2. In a vehicle having axles and driving 50 wheels, the combination with a plurality of side frames having correspondingly disposed openings therein, said openings being disposed a greater distance from each driving axle than the radius of the driving 55 wheels, and a plurality of bearing members disposed in said openings and detachably secured to said side frames, of a rotatable motor member supported by said bearing members and adapted to be removed through 60 one of the side frame openings.

3. In a vehicle having axles and driving 65 wheels, the combination with a plurality of side frames, one of which is provided with an opening therein, said opening being disposed a greater distance from each axle than

the radius of the driving wheels, and a motor member disposed between said side frames and adapted to be removed through said opening, of a supporting member for said motor member disposed within said opening and detachably secured to said side frame.

4. In a vehicle having axles and driving 70 wheels, the combination with a plurality of side frames, one of which is provided with an opening therein, said opening being disposed a greater distance from each axle than the radius of the driving wheels, and a motor armature disposed between said side frames and adapted to be removed through 75 said frame-opening, of bearing means associated with said side frames for supporting said motor armature, one of said bearing means being disposed within said frame opening.

5. In a vehicle having axles and driving 80 wheels, the combination with a plurality of side frames, at least one of which is provided with an opening therein, of a detachable member disposed within said opening and 85 secured to said side frame, and an armature located between said side frames and supported by said detachable member, said armature being adapted to be removed through said opening when the supporting 90 member is detached, while maintaining the position of the driving wheels relative to the side frames unchanged.

6. In a vehicle, the combination with a 95 plurality of side frames, transverse cross-ties therefor, and a magnetizable motor member rigidly supported upon said cross-ties, of a motor armature coöperatively related to said magnetizable member, and a plurality of bearing housings disposed in openings in 100 said side frames and detachably secured to said side frames for supporting said armature, said armature being removable through 105 said frame openings.

7. In a vehicle having axles and driving 110 wheels, the combination with a plurality of side frames having an opening therein, and a motor frame disposed between said side frames, of a motor armature disposed within 115 said motor frame and capable of removal through the end thereof, and means associated with said side frames for supporting said armature and permitting its removal through said opening while maintaining the position of the driving wheels relative to the 120 side frames.

8. In a vehicle, the combination with side 125 frames, a plurality of motor armatures disposed between said side frames and a counter-shaft intermediate said armatures and having a mechanical connection with one end thereof, of bearing members associated with the side frame opposite said mechanical connection for supporting said armatures, said last named side frame having openings 130

of larger dimensions than said armatures in which said bearing members are disposed.

9. In a vehicle, the combination with side frames, a plurality of motor armatures disposed between said side frames, and a counter-shaft intermediate said armatures and having a mechanical connection with one end thereof, of means associated with the side frame opposite said mechanical connection 10 for supporting said armatures and permitting the removal thereof through said side frame.

10. In a vehicle having axles and driving wheels, the combination with side frames 15 and a driving motor having an armature removable through an opening in one of said side frames, said opening being disposed a greater distance from each axle than the radius of the driving wheels, of a driving 20 connection between said armature and one of said axles located outside the opposite side frame to that through which said armature is removable.

11. In a vehicle having axles and driving wheels, the combination with a plurality of side frames, one of which is provided with an opening disposed at a greater distance from each axle than the radius of the driving 25 wheels, of a driving motor comprising a stationary magnetizable frame secured to the side frames and a rotatable armature independently carried by said side frames and mechanically connected to the driving axle 30

upon one side of the vehicle, said armature 35 being longitudinally removable through the opening in the side frame opposite said mechanical connection.

12. In a vehicle having axles and driving wheels, the combination with a plurality of 40 side frames, having relatively large openings therein which are disposed at a greater distance from each axle than the radius of the driving wheels, a magnetizable frame structure supported between said side frames, a 45 plurality of removable bearing housings positioned in the openings of said side frames having flanges adapted to be seated against the outside surface of said side-frames and a plurality of bolts coöperating with said 50 flanges and side frames for rigidly securing said housings in position, of a rotatable armature disposed between said side frames and independently mounted in said bearing 55 housings, said armature being longitudinally removable through the side-frame openings.

In testimony whereof, I have hereunto subscribed my name this 8th day of June, 1914.

MYRA SHIELDS DAVIS,
*Administratrix of the estate of Joseph Le
Conte Davis, deceased.*
